UNITED STATES PATENT OFFICE.

ALBERT S. PAGE, OF EL PASO, TEXAS.

DUMP-CAR-OPERATING MECHANISM.

No. 871,835.

Specification of Letters Patent.

Patented Nov. 26, 1907.

Application filed Jan. 17, 1907. Serial No. 879,696.

To all whom it may concern:

Be it known that I, ALBERT S. PAGE, a citizen of the United States, and a resident of El Paso, county of El Paso, State of Texas, 5 have invented certain new and useful improvements in Dump-Car-Operating Mechanism, of which the following is a specification.

My invention relates to mechanism for 10 operating the discharge means of dump cars wherein the drop doors of the hoppers are unlocked by means of a rotary action applied to their locking means.

While this mechanism is particularly 15 adapted to operate the balanced doors or locking means of the dump car illustrated and described in the patent to Herbert L. Aulls, No. 850,719, April 16, 1907, and is shown in the accompanying drawings as applied 20 to the rock shaft of his car, I do not wish to limit myself to this particular application, for it is obvious that my device may be advantageously applied to several other styles of dump car when the discharge is 25 effected by means of a rotary action upon this locking means, and it is immaterial whether there be one or two hoppers or whether the hoppers be longitudinal or transverse. It is also obvious that my invention can be applied to the operation of 30 the drop doors of bins, storage elevators and like structures. I do not wish to limit myself to this construction as applied to cars alone, and in the following specification and 35 claims the term "car" may be considered as applying to a bin, storage elevator or the like.

It is the object of my invention to construct a simple and inexpensive device 40 whereby the locking means of the hoppers of a dump car may be easily operated at will.

In the accompanying drawings, —Figures 1 to 8, inclusive, represent diagrammatic end views of a car showing the various positions 45 in which the balanced doors may be rotated to form chutes for directing the discharge of the contents of the car to either side or between the rails; Fig. 9 is an end view of a car showing my device applied thereto in 50 elevation; Fig. 10 is a vertical view partly in section of the construction shown in Fig. 9; Fig. 11 is a modification showing a power means applied to the operating mechanism; and Fig. 12 is a vertical sectional view of the 55 same.

Referring to these drawings, and particu-

larly to Figs. 9 and 10, A is a radial arm capable of being revolved in either direction about a fixed center. This arm is preferably provided with a longitudinal slot having a rack A' on one side thereof.

B is a block slidably mounted within the slot or on the radial arm A. This block is moved along the rack A' by rotating a pinion H, which engages the rack on the radial arm A, when the hand wheel J, which is mounted on the extension of the pinion H, is turned. The extension of shaft upon which the pinion H is mounted, also carries the connecting rods E and E' which communicate any 70 movement of the block B to the rock arms F and F' on the shafts G and G'. The shafts G and G' carry the balanced doors g and g' or locking means of the dump car.

The arm A, constituting part of the selective mechanism, is rotated about a fixed center and is set in any one of the various positions desired by releasing the block B from the notch in the ring Q in which it is located, and revolving it until the pawl of the block B drops into the desired notch 1, 2, 3, etc., provided in the ring Q.

The block B is provided with a pawl L which is thrown over when it is desired to 35 advance the block B along the rack A' of the radial arm A carrying with it the connecting rods E and E' for the purpose of rotating one or both of the shafts G and G'.

The following movements of the shafts G and G' on the balanced doors will take place when the hand wheel J is revolved carrying the block B, for the various notches in which the pawl of the radial arm A is placed:

A in notch 1—G rotates to right, G' to left, Fig. 1.

A in notch 2—G rotates to right, G' no rotation, Fig. 2.

A in notch 3—G rotates to right, G' to right, Fig. 3.

A in notch 4—G no rotation, G' to right, Fig. 4.

A in notch 5—G rotates to left, G' to right, Fig. 5.

A in notch 6—G rotates to left, G' no rotation, Fig. 6.

A in notch 7—G rotates to left, G' to left, Fig. 7.

A in notch 8—G no rotation, G' to left, Fig. 8.

The shafts are returned to their normal positions, as shown in Fig. 1, in each case by

throwing over the pawl L and revolving the hand wheel J in such direction as to carry the block B back to the fixed center where it remains locked until the pawl L is again thrown over for the next discharge of the car. Although this device is preferably placed on the end of the car, it is obvious that it may be placed on the sides of a car having transverse hoppers.

In Figs. 11 and 12, I have shown a modification of my device wherein power means are applied for actuating the operating mechanism. This construction is substantially the same as shown in Figs. 9 and 10, except that the radial arm A is provided with an extension in the form of a cylinder P having a piston therein, the piston rod of which is attached to the sliding block B. This cylinder is provided with an air passage P' leading back to the center of the radial arm A, where it connects with the air passage in the stationary block or fixed center N leading to the air supply pipe provided with a stop cock P². The stationary block N permits a concentric movement between itself and the radial arm A by means of the central projection of arm A engaging the same. A packing R, of any convenient style, is provided at this point between the projection of arm A and block N to make an air tight joint.

From this description, it is seen that my device consists of a selective mechanism which includes a radial arm A and the notched ring C around which it revolves and the operating mechanism which includes the movable block B and the rack A' on the radial arm A along which it moves, and means for moving the same.

What I claim is:—

1. In combination with drop doors having locking means, means for rotating said locking means comprising a single selective mechanism and an operative mechanism therefor, substantially as described.

2. In combination with drop doors having locking means, a selective mechanism comprising a radial arm, a rack on said arm, a block having a pinion engaging said rack and adapted to be moved along said arm, and means connecting said block with said locking means.

3. In combination with a dump car having locking means for its hoppers, means for actuating said locking means comprising a sin-

gle selective mechanism and an operating mechanism therefor, substantially as described.

4. In combination with a dump car having locking means for its hoppers, a selective mechanism comprising a radial arm, a rack on said arm, a block having a pinion engaging said rack adapted to be moved along said arm, and means connecting said block with said locking means.

5. In combination with a dump car having a balanced locking means for its hoppers, means for rotating said locking means comprising a radial arm, a block adapted to be moved along said arm, means for moving said block along said arm, and means connecting said block with said locking means.

6. In combination with a dump car having balanced locking means for its hoppers, means for rotating said locking means comprising a radial arm, a block adapted to be moved along said arm, a cylinder having its piston connected with said block for moving the same, and means connecting said block with said locking means.

7. In combination with a dump car having balanced locking means for its hoppers, means for rotating said locking means comprising a radial arm having a latch, a block adapted to be moved along said arm, means for moving said block, means connecting said block and said balanced locking means, and a notched ring adapted to be engaged by the latch on said arm.

8. In combination with a dump car having balanced locking means for its hoppers, means for rotating said locking means comprising a radial arm, a block adapted to be moved along said arm, means for moving said block, and a pawl on said block for locking the same in its normal position.

9. In combination with a dump car having locking means for its hoppers, means for unlocking said locking means comprising a single mechanism combining a selective mechanism and an operative mechanism, substantially as described.

In testimony whereof, I have signed my name to this specification, in the presence of two subscribing witnesses.

ALBERT S. PAGE.
